UNITED STATES PATENT OFFICE.

ALBIN K. LONGREN, OF TOPEKA, KANSAS.

AIRPLANE-CONTROL-SURFACE RIB CONNECTION.

Application filed September 1, 1922. Serial No. 585,682.

To all whom it may concern:

Be it known that I, ALBIN K. LONGREN, a citizen of the United States, residing at Topeka, in the county of Shawnee and State of

5 Kansas, have invented certain new and useful Improvements in Airplane-Control-Surface Rib Connection; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

15 This invention refers to means for connecting the ribs to the hinge tube in any of the control surfaces of an airplane, such as the elevators, rudders, or ailerons, and the invention particularly contemplates the kind 20 of screws used and the manner of their application in order to influence the tension of the metal straps used in attaching the wooden ribs to the metallic hinge tube.

The novel means by which these screws are 25 introduced into the part which they engage in order to insure the necessary tightness or tension in the metal straps will be particularly referred to hereinafter, reference being made to the accompanying drawings, in 30 which—

Fig. 1 is a perspective view of the tail end of an airplane constructed in accordance with my invention.

Fig. 2 is a transverse sectional view 35 through the tail end of the fuselage, showing the elevator control arms and the elevator hinge tube in elevation.

Fig. 3 is a fragmentary view, partly in 40 section, showing one of the ribs.

Fig. 4 is a similar view showing the metal 45 hinge tube and the metal strap for securing the ribs thereto, the tensioning screw being in position to enter its opening, and

Fig. 5 is a fragmentary perspective view 50 of an elevator frame.

For the purpose of illustration I will 55 describe in detail the construction of the elevators, it being distinctly understood that precisely this same method of construction applies to the ailerons, and rudders as well as to the elevators.

Referring now to the drawings by numerals of reference:

1 designates the tail end of a fuselage provided with horizontal stationary surfaces or

stabilizers 2 and 3, and a vertical stationary surface or fin 4.

The elevator is built up on a metal tube 8—the hinge tube—which forms the forward edge of said control surface. The opposite, or trailing edge, and the ends are formed by a smaller metal tube 10, 11, and 12, bent and attached to the ends of the hinge tube as shown in Fig. 1.

The rectangular frame thus formed is 65 filled in with numerous wooden ribs 13, suitably slotted at 14 for lightening purposes. A brace 22 may connect the smaller metal tube parts 11 and 12, same passing through the slots 14 of the ribs 13 as clearly shown 70 in Fig. 1. The rear end of each rib is cut or notched, as at 15, to fit the curve of the trailing edge tube 10, and the forward end of each is rounded out as at 16 to fit the curve 75 of the hinge tube 8.

The ribs 13 are rigidly fastened to the hinge tube 8 by means of metal straps 17, which pass around the hinge tube 8 and have their ends secured to the ribs 13 by means of screws 18 and 19.

In order to provide for the maximum 80 strength and to prevent the rib from splitting, I bore two holes 20 and 21 in the end of the rib 13. These holes are drilled slightly less in diameter than the diameter of the 85 screws 18 and 19. I prefer to use machine screws because in actual practice, I have found that they afford the most secure means for fastening the straps. By offsetting the holes 20 and 21 there is very little chance of 90 the ribs being split by the screws 18 and 19, as would be the case if the holes were in alignment and gave one continuous hole entirely through the rib.

In fastening the rib to the hinge tube 8 I 95 prefer to first attach one end of the metal strap 17 to the rib by means of the screw 18; the other screw 19 is then inserted in the hole in the other end of the strap 17 with its point 100 projecting through slightly. The strap 17 is then bent around the hinge tube 8 and the point of the screw 19 inserted in the hole 21, as shown in Fig. 4. When the screw 19 has been given a few turns to get it firmly started in the hole 21 it is then straightened up until its axis is in actual alignment with the 105 axis of the hole 21. The proper length for the strap 17 having been previously calculated provides that this straightening of the screw 19 will place the proper tension in the 110

metal strap 17 for the making of a tight connection between the rib 13 and the hinge tube 8. The strap 17 is then to be attached to the hinge tube 8 by means of rivets or screws, brazing or spot welding—either electric or autogenous, as shown at 31.

This work of assembling can be done by inexperienced workmen and in actual practice I have found that this simple and inexpensive method greatly reduces the ultimate 10 cost of the airplane.

What I claim and desire to secure by Letters-Patent is:

1. A control surface rib connection for 15 airplanes comprising a frame having a metal hinge tube forming one side thereof, a plurality of wooden ribs at right angles to said hinge tube, metal straps passing around said hinge tube, and screws offset one with the other and fastening the straps to the ribs the operative positioning of the last screw 20 tensioning the strap for the making of a tight connection between the strap and hinge tube.

2. A control surface rib connection for 25 airplanes comprising a frame including a metal hinge tube at its forward or leading edge, a smaller metal tube for its rear or trailing edge, having end portions connecting 30 with the hinge tube slotted, wooden ribs extending transversely of the frame and having their ends cut or notched in order to fit the hinge tube and the trailing edge of the smaller tube, metal straps passing around 35 the hinge tubes, a bracing element passing through the slots of the wooden ribs and connecting the end portions of the trailing tube and means for attaching the ends of the straps to the ribs comprising screws re-

ceived in offset openings in the ribs, the 40 screws exerting tension on the straps.

3. A control surface rib for airplanes comprising an elongated wooden member having a longitudinal slot therein to reduce weight, the respective ends of the member being 45 notched to fit oppositely located supports, the member being larger at one end than at the other and provided at its larger end with offset screw holes on opposite sides thereof.

4. A control surface rib for airplanes comprising an elongated wooden member having a longitudinal slot to reduce weight, the respective ends of the member being notched to engage bars of a supporting frame, one 50 end of the member being larger than the other, the larger end being provided with two offset screw holes on opposite sides, a metal strap for securing one end of the rib to its support, and machine screws passing through the ends of the metal strap and engaging offset screw holes in the rib.

5. A control surface rib for airplanes comprising an open frame, including a hinge tube, a plurality of wooden ribs mounted in 55 the frame at right angles to the hinge tube and each having a notch embracing the inner side of the hinge tube, a metal strap connected at one end to each rib and passing around and embracing the outer side of said hinge tube and at its opposite end connected 60 to the respective ribs, the devices for connecting the ends of the straps to the respective ribs entering the latter in opposite directions and in spaced overlapping relation 65 adjacent the hinge tube.

In testimony whereof I affix my signature.

ALBIN K. LONGREN.
